(57) **CLAIM**

The ornamental design for a wheel cleaning brush as shown
and described.

DESCRIPTION

FIG. 1 is a perspective view of a new and ornamental wheel
cleaning brush;

FIG. 2 is a front elevation view thereof;

FIG. 3 is a rear elevation view thereof;

FIG. 4 is a first side elevation view thereof;

FIG. 5 is a second side elevation view thereof;

FIG. 6 is a top plan view thereof; and,

FIG. 7 is a bottom plan view thereof.

In the drawings, the broken lines illustrate portions of the
article and form no part of the claimed design.
